UNITED STATES PATENT OFFICE

2,598,441

VACUUM FILLING MACHINE

Ivan H. Risser, Glenview, Ill., assignor to U. S. Bottlers Machinery Company, Chicago, Ill., a corporation of Illinois

Application March 1, 1950, Serial No. 147,043

9 Claims. (Cl. 226—113)

1

The present invention relates to a novel vacuum filling machine of the type in which a plurality of bottles or other containers are simultaneously filled to a predetermined height by multiple filling tubes movable vertically relative to the bottles or containers to be filled.

Among the objects of the above invention is the provision of a novel means and mechanism for raising and lowering a plurality of vacuum filling tubes and simultaneously therewith operating a novel vacuum control valve connected to a vacuum pump and to a pair of vacuum overflow cylinders in such manner that operation of the elevating mechanism and control valve are simultaneously effected, and such operation of the control valve alternately connects the pump to one and then to the other of the vacuum overflow cylinders.

The present invention further comprehends the provision of a novel valve and valve actuating and vacuum control mechanism associated with a vacuum pump for controlling the overflow from a plurality of filling tubes to a pair of vacuum overflow cylinders.

Another object of the present invention is the provision of a novel cable-lift or actuating mechanism for simultaneously raising and lowering multiple vacuum filling tube assemblies in such manner as to require minimum effort and attention on the part of the operator of the machine. The invention further comprehends a novel cable lift assembly which permits the filling of containers of widely varying dimensions.

Yet another object of the present invention is the provision in a vacuum filling machine of a novel cable operating mechanism in which the cables are connected to a cable lift pulley or sheave and to a pair of spaced vertical raising shafts or supports carrying at their upper end a manifold assembly and multiple filling tube assemblies carried thereby, the cables passing over a plurality of pulley wheels so arranged that rotation of the lift pulley or sheave through a relatively small arc causes the cables to raise or lower the raising shafts or vertical supports and the manifold and tube assemblies carried thereby into and out of filling engagement with a plurality of containers.

The present invention further comprehends the provision of a novel valve operating mechanism including a cable lift pulley or sheave, cables having their ends connected to and wound about the pulley or sheave and with the cables passing over a plurality of pulley wheels at the opposite sides of the machine, a cable clamp connecting an end of each cable to one of the elevat-

2

ing or raising shafts vertically movable through the cabinet or base housing of the machine, and these elevating or raising shafts supporting and carrying at their upper end a manifold assembly and a plurality of spaced filling tubes for supplying the liquid to be dispensed.

A further object of the present invention is the provision of a novel vacuum control valve belt in the form of a coil or expansible spring carried by and rotatable with the cable lift pulley or sheave for alternately rotating the control valve through a predetermined arc of travel.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawings, and while there is shown therein a preferred embodiment, it is to be understood that the same is susceptible of modification and change, and comprehends other details, arrangements of parts, features and constructions without departing from the spirit of the invention.

In the drawings:

Figure 1 is a top plan view of the present novel vacuum filling machine.

Fig. 2 is a view in side or end elevation of the vacuum filling machine but with the end panel removed and a portion of the end wall of the cabinet broken away to permit more complete disclosure of the operating parts.

Fig. 3 is a view part in front elevation and part in vertical cross-section of the novel vacuum filling machine, the section being taken in a plane represented by the line 3—3 of Fig. 2.

Fig. 4 is a diagrammatic or schematic view of a vacuum filling system as employed in the present machine.

Fig. 5 is a view in vertical cross-section through the cable lift assembly including the lift actuating mechanism and sheave or cable lift pulley with its cable for raising and lowering the multiple filling tubes and the spring or flexible vacuum control valve belt for operating the valve, the view of the sheave or cable lift pulley being taken in a plane represented by the line 5—5 of Figs. 6 and 9.

Fig. 6 is a fragmentary view in rear elevation of the sheave or cable lift pulley and showing the manner of connecting and anchoring the ends of the cables thereto.

Fig. 7 is a view in vertical cross-section through

3

the rotatable vacuum control valve assembly for controlling the application of vacuum and the overflow from the filling mechanism, the view being taken in a plane represented by the line 1—7 of Fig. 8.

Fig. 8 is a view in rear elevation of the control valve.

Fig. 9 is a view in front elevation of the cable lift assembly.

Fig. 10 is a view in front elevation of the front or end cap for the vacuum control valve, but with its slot disposed in a position different from that in Fig. 7.

Referring more particularly to the disclosure in the drawings and to the novel embodiment therein selected to illustrate the present apparatus, the vacuum filling machine disclosed comprises a base or cabinet 1 (Figs. 1, 2 and 3) providing an enclosure or housing for the operating mechanism and a support for a feed table or container feed bed 2, a pair of vacuum overflow separator cylinders 3 and 4, one at each end of the unit, a liquid supply tank or reservoir 5 shown as located at the rear of the unit, and a manifold assembly 6 supported at its opposite ends and carried by the upper end of a pair of raising shafts or uprights 7 each slidably mounted and vertically movable in a supporting sleeve or collar 8 supported upon the top of the cabinet 1.

The manifold assembly 6 is horizontally disposed and comprises a vacuum manifold 6^a, and a pair of manifold bar brackets 9 mounted upon the opposite ends of a tube manifold bar 10, each bracket in turn being mounted upon the upper end of one of the raising shafts or uprights 7 whereby the vacuum manifold assembly is movable vertically. Mounted in spaced relation upon and depending from the manifold assembly are a plurality of filling tube assemblies 11, each assembly having a filling head 12 connected to one end of a flexible tube 13 receiving and supplying liquid from the liquid supply tank or reservoir 5 to each filling head 12. A supply line A is connected to the tank or reservoir 5 to supply liquid thereto.

The vacuum filling system employed in the present apparatus is shown diagrammatically in Fig. 4 in which the liquid 14 with which each bottle or container 15 is to be filled is withdrawn from the supply tank 5. This liquid under pressure is forced through a flexible tube 13 to each filling head 12 of a vacuum filling tube 11, and from the head downwardly through the communicating passage in an outer tube 16 encompassing an inner or vent tube 17. Secured to the exterior of the outer tube 16 at a point spaced from the end thereof, is a clamp 18 carrying a sealer rubber 19 which when seating upon the neck or upper open end of a bottle or container 15 forms a sealing contact therewith. The inner or vent tube 17 is connected by a flexible tubing 20 with a vacuum overflow separator cylinder 3 which in turn is connected to a vacuum pump 21 by a tubing 32. Another section of tubing 22 returns the overflow from the cylinder 3 through a flapper valve 23.

When filling the bottles with the liquid to the desired predetermined height, relative vertical movement between each bottle and its vacuum filling tube assembly 11 with its outer and inner tubes 16 and 17 is effected whereby the lower end of each filling tube assembly is inserted in a bottle or container until the sealer rubber 19 forms a sealing contact with the neck or end of the bottle. Each sealer rubber and its clamp 18 are affixed to the outer tube 16 but adjustable thereon to adjust

4

the height of the liquid to be dispensed. This filling operation allows the liquid from the supply tank 5 to pass through a filling tubing 13 to a filler head 12 and then through an outer tube 16 and discharge into the bottle or container until a predetermined height is reached. When the liquid reaches a height approximately that of the lower end of the inner or air vent tube 17, flow of liquid is automatically discontinued.

When the filler tube assembly is withdrawn from each bottle or container and the seal between the bottle and the sealer rubber 19 is broken, further passage or flow of liquid is prevented. As vacuum is continuously applied to the inner tube 17 by the vacuum pump 21 through an overflow separator cylinder, leakage of liquid from each filling tube assembly is prevented or reduced to a minimum.

In the disclosed illustrative embodiment of the complete assembly, a pair of overflow separator cylinders 3 and 4 are provided, the cylinder 3 being connected to one end 24 of the vacuum manifold 6^a of the manifold assembly 6 by a section of flexible tubing 25 and the cylinder 4 is connected to the other end 24 of the vacuum manifold 6^a by a section of flexible tubing 26. This vacuum manifold is shown as connected to each filling tube assembly 11 by means of a relatively short section of flexible tubing 27 connected to the upper end of its inner or air vent tube 17.

Vacuum is supplied to the flexible tubing 27 of the inner or air vent tube 17 of each filler assembly by means of the vacuum pump 21 (see Figs. 2 and 4). Connected to and controlling the vacuum from this pump is a control valve assembly including a control valve plug 28 rotatably mounted in a housing 29. Connected to the rear 30 of the stationary valve housing are three sections of flexible tubing (Figs. 2 and 7) including a flexible tube 31 connected to the pump 21, a flexible tube 32 connected to the overflow separator cylinder 3, a flexible tube 32^a connected to the overflow separator cylinder 4 and an opening 33 connected to the atmosphere.

The tubes 32 and 32^a connecting to the overflow cylinders 3 and 4, respectively, open into a pair of arcuate slots 34 and 35 also adapted to be connected to the vacuum pump 21 and to the atmosphere, so disposed and arranged that in one position of the rotatable control valve plug 28, the overflow separator cylinder 3 is connected to atmosphere through the opening 33, while at the same moment the overflow separator cylinder 4 is connected to the vacuum pump 21 through the tube 31 (see Figs. 2 and 8), and when the valve plug 28 is rotated through an arc of approximately 90° from the position shown in Fig. 8, the overflow cylinder 4 is connected to the atmosphere and the cylinder 3 is connected to the pump.

The rotatable control valve is pinned or keyed upon a stub shaft 36 which extends through and is journalled in a closure or end plate 37 of the valve housing 29, the extended end of the shaft having pinned thereon a vacuum control valve pulley wheel 38 provided with a substantially V-shaped groove 39 for receiving a resilient control valve belt 41 for rotating the pulley wheel, this belt being shown as anchored to the wheel by a set screw 42. The end plate or closure disc 37 is provided with an arcuate slot 43, and the rotatable valve plug 28 is cored and tapped to receive a stop pin or screw 44 limiting the travel of the plug to approximately 90°.

The control valve is shown as cored to receive a cup-shaped sleeve providing a valve spring

plunger 45 encompassing a compression spring 46 bearing against the base of the sleeve and forcing the plug in seating engagement with the interior of the rear wall 30 of the housing. As shown in dotted lines in Fig. 8, the arcuate slots 34 and 35 as well as the arc of rotation of the control valve, are limited to an arc of approximately 90°. As the resilient belt 41 slips upon reaching the end of the intended arc of travel of the valve, there is no danger of the valve overrunning.

To rotate the control valve through the resilient belt and to raise and lower the raising shafts or supporting uprights 7 with the manifold assembly 6 and the vacuum filling tubes 11 carried thereby, the present invention comprehends the provision of a novel cable lift assembly and operating mechanism therefor. It comprises an actuating handle 47 connected through its shank or stud 48 to an eccentric weight 49. Rotation of this weight causes rotation of a shaft 50 keyed or pinned to a sheave or cable lifting pulley 51 and operating in a bearing 52 secured to the wall of the cabinet. This sheave or pulley is formed with a plurality of substantially V-shaped grooves, a groove 53 and adjacent grooves 54, the groove 53 receiving and rotating the spring belt 41, while the grooves 54 are each adapted to receive and securely anchor thereto the opposite ends 55 and 56 of a pair of lifting cables 57 and 57a, respectively (see Figs. 5 and 6). One lifting cable is taken off and extends over a series of pulley wheels 58 at one side of the cabinet, while the other lifting cable is taken off and extends over similar pulley wheels 58 at the other side of the cabinet.

Attached to each lifting cable adjacent the opposite ends of the cabinet, is a cable clamp assembly 59 carried at the lower end of the vertical raising shafts or supporting uprights 7. Each cable clamp assembly is provided with a sleeve-like member or raising shaft spacer 60 affixed to the lower end of the raising shafts 7 and a depending and laterally projecting cable clamp 61 secured to the cable and joined together by a bolt and nut 62.

Mounted on the face of the eccentric weight 49 is a lift pulley adjusting disc 63 secured to the end of the shaft 50 and locked to the eccentric 49 by a cap screw or lock bolt 64 passing through an arcuate slot 65 in the plate or disc 63. This adjustment permits variation of the stroke or throw of the handle 47 and the weight 49 to thereby adjust the arc of movement of the lift pulley 51 and the raising shafts 7 depending upon the movement to be accorded the filling tube assemblies 11. In addition, the eccentric is adapted to be held or retained in various adjusted positions by means of a spring-pressed locking pin or detent 66 having a tooth or projection 67 adapted to seat in a toothed segment or ratchet rack 68. Although the movement or height of travel of the filling tube assemblies may be varied as above described, to accommodate containers of different height, such travel to and from filling position is sufficient to at all times rotate the vacuum control valve to its proper operative positions.

The vacuum overflow cylinders 3 and 4 are each shown as provided with a vacuum gauge 70, a vacuum relief valve 71, a ball check valve 72 in the passage or connection with the flexible tubing 25 and 26 and a return drain 22 from each cylinder returning the overflow back to the liquid supply tank 5.

Bottles or other containers are placed or fed onto the feed table or bed 2. To allow for their proper placing and alignment with the filling

tube assemblies 11, this feed table or bed is provided with an adjustable rear guide rail 73 upon a pair of spaced laterally and rearwardly projecting supporting arms 74 each adjustably mounted in a rear guide rail support 75, and with a front guide rail 76 that is also mounted for lateral adjustment on the container feed bed 2 by means of spaced elongated slots 77 and locking screws 78.

By means of the present novel construction and assembly, movement of the handle through the predetermined arc of movement lowers and raises the elevating shafts or supporting uprights 7, and when moved in a clockwise direction to their lowered position the filling tube assemblies 11 function to fill the bottles or containers aligned therewith to the desired filling height. Simultaneously with the lowering of the filling tubes, the vacuum control valve plug 29 is rotated through an arc of approximately 90° whereby vacuum is applied to the overflow cylinder 3 and the overflow cylinder 4 is open to the atmosphere. This reversal is automatically accomplished by rotation of the valve, it being evident that it requires but a small arcuate movement of the lift pulley 51 to move the valve plug to the limits of its movement through the resilient belt 41.

When the handle is moved to the left or in a counterclockwise direction, the elevating shafts or supporting rods 7 are raised and carry therewith the filling tube assemblies to raised, inoperative position, and simultaneously therewith the vacuum control valve plug 29 is rotated to the position in which vacuum is applied to the vacuum overflow cylinder 4 and the vacuum overflow cylinder 3 is open to the atmosphere. This plug 29 is limited in its arc of travel by the slot 43 in the end plate 37 and the stop pin 44, regardless of the throw of handle 47 and the cable lift pulley or sheave 51 by reason of the resiliency of the vacuum control valve belt 41.

The vacuum filling tube assemblies 11 may be positioned at any desired elevation to accommodate bottles or containers of any desired height or capacity.

Having thus disclosed the invention, I claim:

1. In a vacuum filling apparatus for filling a plurality of containers with liquid to a prescribed height from a liquid supply tank, a support for receiving and retaining the containers during filling, a plurality of vacuum filling tube assemblies for supplying the containers with liquid and each having an air vent tube and a liquid supply tube connected to the supply tank, a manifold connecting the air vent tubes, mechanism for raising and lowering the filling tube assemblies relative to the support, a vacuum pump, a pair of vacuum overflow cylinders connected to the manifold, a vacuum control valve assembly having a plurality of ports one connected to the vacuum pump, one connected to the atmosphere and one to each of the overflow cylinders, said valve assembly including a rotatable valve member having a pair of arcuate slots each adapted to alternately connect one overflow cylinder to the atmosphere and the other to the vacuum pump whereby when the valve is rotated to one position and the filling tube assemblies are lowered, one of the overflow cylinders is connected to the atmosphere and the other to the vacuum pump, and when the valve is rotated to its other position the other overflow cylinder is connected to the atmosphere and the first mentioned overflow cylinder

is connected to the vacuum pump, and a common manually operable actuating means connected to the rotatable valve and to the raising and lowering mechanism for simultaneously actuating the raising and lowering mechanism and the rotatable valve member.

2. In a vacuum filling apparatus for filling a plurality of containers with liquid to a prescribed height from a liquid supply tank, a support for receiving and retaining the containers during filling, a plurality of vacuum filling tube assemblies for supplying the containers with liquid and each having an air vent tube and a liquid supply tube connected to the supply tank, a pair of vacuum overflow cylinders connected to the air vent tubes, a control valve assembly having a housing provided with a plurality of ports one connected to a source of vacuum, one open to the atmosphere and one to each of the overflow cylinders, a rotatable valve member in the housing having passages alternately connecting the port leading to each cylinder to the atmosphere and then to the source of vacuum, mechanism for moving the filling tube assemblies into and out of filling position, and a common manually operable means connected to said mechanism and to the valve member for simultaneously moving the filling tube assemblies into and out of filling position and alternately rotating the valve for alternately connecting one cylinder and then the other to the source of vacuum and then to the atmosphere.

3. In a vacuum filling machine for simultaneously filling a desired number of bottles or other containers with liquid to a predetermined height from a liquid supply tank, a cabinet having a container feed bed for supporting the containers during the filling operation, raising shafts mounted for vertical movement in the cabinet, supporting means mounted upon the upper end of the raising shafts, a plurality of filling tube assemblies carried by the supporting means for receiving and dispensing a predetermined height of liquid to the containers, a vent tube and a liquid supply tube connected to each filling tube assembly, a vacuum manifold carried by the supporting means and connected to each vent tube, a pair of vacuum overflow cylinders connected to the vacuum manifold and to a source of vacuum, a vacuum control valve having ports connecting to the source of vacuum, to the atmosphere and to the overflow cylinders, cable lifting mechanism for raising and lowering the shafts and simultaneously operating the valve and including a cable lift pulley and cables connected to the raising shafts and a belt connected to and alternately rotating the valve, and a common actuating control means for actuating the pulley whereby to move the cables and shafts and simultaneously therewith move the belt to alternately rotate the valve.

4. In a vacuum filling machine for the simultaneous filling of a plurality of bottles or other containers with liquid from a supply tank, a housing having a container feed bed for supporting and positioning thereon the containers to be filled, a plurality of filling tube assemblies positioned above the feed bed and housing and each adapted to supply liquid to a container, each assembly including an air vent tube and a liquid supply tube connected to the supply tank, a vacuum manifold connecting the air vent tubes, a pair of vacuum overflow cylinders connected to the manifold, a vacuum pump, valve mecha-

nism connected to the overflow cylinders, vacuum pump and atmosphere for alternately connecting a cylinder to the vacuum pump and then to the atmosphere, and a common manually actuated control means for operating the valve mechanism and simultaneously therewith raising and lowering the filling tube assemblies.

5. In a vacuum filling machine for the simultaneous filling of a plurality of containers with liquid to a predetermined height, a feed table, multiple filling tube assemblies vertically movable with respect to the feed table and the containers to be filled, and mechanism for raising and lowering the filling tube assemblies relative to the containers and into and out of filling position, said mechanism including spaced raising shafts carrying at their upper ends the filling tube assemblies, a lift cable connected to each raising shaft, a cable lift assembly having a cable lift pulley to which the ends of the lift cables are connected for moving the cables, shafts and filling tube assemblies in unison, and common manual actuating and control means for rotating the cable lift pulley through a predetermined arc to raise and lower the raising shafts simultaneously.

6. In a vacuum filling machine for the simultaneous filling of a plurality of bottles or other containers with liquid from a supply tank, a housing supporting and positioning thereon the containers to be filled, a plurality of filling tube assemblies mounted for vertical movement above the housing and each adapted to supply liquid from the supply tank to a container to a predetermined height, a vacuum pump, a pair of vacuum overflow cylinders connected to the filling tube assemblies and to the pump, valve mechanism connected to each cylinder, to the pump and to the atmosphere in such manner that each cylinder is alternately connected to the pump and then to the atmosphere whereby a vacuum is continuously applied to the filling tube assemblies but alternately to the cylinders to permit the overflow from the assemblies to alternately enter one cylinder while the other cylinder is draining the overflow collected therein to the supply tank, and common actuating mechanism for vertical movement of the filling tube assemblies and for rotation of the valve mechanism.

7. In a vacuum filling machine, a plurality of filling tubes each connected to a liquid supply and provided with an air vent, a vacuum pump, a pair of vacuum overflow cylinders connected to the pump and to the air vents of the filling tubes for applying a vacuum to these tubes and withdrawing any overflow during the filling operation, a valve for alternately connecting these cylinders to the vacuum pump and to the atmosphere, and common manually actuated mechanism for raising and lowering the filling tubes and simultaneously operating the valve to control the vacuum to the cylinders.

8. In a vacuum filling machine of the type in which a plurality of containers are simultaneously filled with a liquid to a predetermined height, a plurality of vacuum filling tubes each connected to a liquid supply and to an air vent, a vacuum pump, a pair of vacuum overflow cylinders connected to the filling tubes, a valve for alternately connecting a cylinder to the pump and then to the atmosphere, and common manually actuated means for lowering the filling tubes into contact with the containers to be filled and raising and removing the filling tubes from the containers when the containers are filled and simul-

taneously therewith operating the valve whereby during the lowering operation one cylinder is connected to the vacuum and the other to the atmosphere.

9. In a vacuum filling machine of the type in which a plurality of containers are simultaneously filled with a liquid to a predetermined height, a plurality of vacuum filling tubes each connected to a liquid supply and to an air vent, a vacuum pump, a pair of vacuum overflow cylinders connected to the filling tubes, a valve for alternately connecting a cylinder to the pump and then to the atmosphere, cable lift mechanism for lowering the filling tubes into contact with the containers to be filled and raising and removing the filling tubes from the containers when the containers are filled and a vacuum control valve belt operated by the cable lift mecha-

nism for simultaneously operating the valve whereby during the lowering operation one cylinder is connected to the vacuum and the other to the atmosphere.

IVAN H. RISSEK.
